Inventor

H.E. Boyd.

By John Murphy Jr. Attorney

UNITED STATES PATENT OFFICE.

KYLE E. BOYD, OF LINDSIDE, WEST VIRGINIA.

RAILWAY TIE AND RAIL-FASTENING MEANS.

Application filed June 7, 1924. Serial No. 718,565.

To all whom it may concern:

Be it known that I, KYLE E. BOYD, a citizen of the United States, residing at Lindsie, in the county of Monroe and State of West Virginia, have invented certain new and useful Improvements in Railway Ties and Rail-Fastening Means; and I do hereby declare the following to be a full, clear, and exact description of the invention, such as will enable others skilled in the art to which it appertains to make and use the same.

This invention relates to railway ties and rail fastening means, and has for one of its objects the provision of a metallic tie for mine railways which shall be comparatively thin in order to provide more room between the heads of the rails and the roof of the mine than is afforded by the wood ties now in use, whereby to permit the cars to be more readily loaded or to permit the use of cars having bodies greater in height than the bodies of the cars now in use.

A further object of the invention is the provision of means through the medium of which rails may be easily and quickly secured to the tie, which will form a permanent part of the tie, which will prevent the spreading or tilting of the rails, and which will obviate the use of rail joints.

With the above and other objects in view, the invention consists in the construction, combination and arrangement of parts hereinafter fully described and claimed, and illustrated in the accompanying drawings, wherein:

Figure 1 is a view in side elevation of a railway tie and rail fastening means constructed in accordance with my invention.

Figure 2 is a top plan view of the tie and rail fastening means.

Figure 3 is a detail top plan view of the tie,

Figure 4 is a detail perspective view of one of the abutments of the rail fastening means,

Figure 5 is a similar view of the other abutment of the rail fastening means,

Figure 6 is a detail perspective view of one of the clamps of the rail fastening means,

Figure 7 is a similar view of the other clamp of the rail fastening means,

Figure 8 is a detail sectional view taken on the plane indicated by the line 8—8 of Figure 2,

Figure 9 is a detail sectional view taken on the plane indicated by the line 9—9 of Figure 2, and

Figure 10 is a detail sectional view taken on the plane indicated by the line 10—10 of Figure 2.

Referring to the drawings by reference numerals, 1 designates a rail tie which is made of metal, which may be of any length and width found necessary in practice, and which is preferably one-third of an inch in thickness in order to provide more room between the tops of the rails supported thereby and the roof of the mine than is afforded by the wood ties now in use so as to permit the cars to be more readily loaded or to permit the use of cars having bodies greater in height than the bodies of cars now in use.

The rail fastening means comprises abutments 2 and 3 which are permanently and rigidly secured to the upper side of the tie 1 near the ends thereof, and clamps 4 and 5 which are permanently and adjustably secured to the upper side of the tie between the abutments. The abutment and clamp shown respectively in Figures 5 and 6 are adapted to be employed to secure an intermediate portion of a rail to the tie, and the abutment and clamp shown respectively in Figures 4 and 7 are adapted to be employed to secure the end portions of two rails to the tie, as clearly illustrated in Figure 2.

The abutments 2 and 3 are of hollow construction, they increase in height and width in the direction of their inner ends, and they are provided at the lower edges of their side walls 6 with securing lugs 7. The lugs 7 pass through openings 8 in the tie 1, and their lower ends are upset to secure the abutments 2 and 3 in place against any accidental movement with respect to the tie. The openings 8 are, as shown in Figure 8, counterbored at the under side of the tie 1 to receive the upset portions of the lugs 7.

The side walls 6 of the abutment 2 extend inwardly beyond the inner edge of the top wall 6^a thereof. The projections 9 thus provided have downwardly and inwardly inclined upper edges 10, upwardly and inwardly inclined lower edges 11 and intermediate vertical edges 12. Due to the peculiar formation thereof, the inner end of the abutment 2 conforms to and is adapted to fully abut the outer side of the rail with which it is associated. The abutment 3 is provided at its inner end with laterally extending flanges or bars 13 which are formed integrally with the side walls 6 thereof. The upper and lower edges of the flanges 13 are beveled as shown at 14, and due thereto the formation of the inner end of this abutment corresponds to the formation of the outer side of the rail ends with which this abutment is associated. The flanges 13 are provided with bolt receiving openings 15.

The clamps 4 and 5 are provided with bodies 16 which are of elongated formation and which are provided at their outer ends with upwardly and outwardly extending rail base flange contacting members 17. A bar 18 is secured to the lip or flange 17 of the clamp 4, and it is provided with beveled edges 19. The bar 18 contacts with the outer side of the rail web and with the rail head and rail base flange. The lip or flange 17 of the clamp 5 is provided with a bar 18^a which differs from the bar 18 in that it is longer and provided with bolt receiving openings 15. The bodies 16 are provided with elongated slots 21 which communicate at their inner ends with lateral notches 22. Rivets 23 which are secured to the tie 1 and which pass through the slots 21 are adapted to adjustably secure the clamps 4 and 5 to the tie 1 in order to permit them to be moved into and out of locking engagement with the rails. The rivets 23 pass through openings 23^a in the tie 1 and their lower ends are upset to retain them against casual movement with respect to the tie, as shown in Figure 9, the openings 23^a being counterbored at the under side of the tie to receive the upset portions of the rivets. The elongated slots 21 permit the clamps 4 and 5 to be moved in the direction of and away from the rails, and after the clamps are moved into contact with the rails they are moved laterally with respect to the tie 1 in order that the rivets 23 may occupy the notches 22. When the rivets 23 occupy the notches 22, the clamps 4 and 5 are secured in contact with the rails against inward casual movements. To secure the clamps 4 and 5 against any pivotal movement upon the rivets 23, bolts 24 are provided. The bolts 24 extend through angular openings 25 in the tie 1, and through openings 26 in the clamps 4 and 5. The heads 27 of the bolts 24 are of angular formation and are countersunk in the under side of the tie.

The bolts are removable in order to permit the clamps 4 and 5 to be moved into and out of rail holding position.

As shown in Figures 1 and 2 a rail 28 is positioned between the abutment 2 and clamp 4, and the meeting ends of two rails 29 and 30 are positioned between the abutment 3 and clamp 5. After the rails are in position, the clamps 4 and 5 are moved into contact with them, the bolts 24 are then applied, and bolts 31 are thence passed through the flanges 13 of the abutment 3 and the bar 18^a of the clamp 5. As this is all that has to be done, in order to firmly secure the rails to the tie, it should be apparent that the rails may be secured to the tie easily and quickly. It should also be apparent that the structure is durable, strong and efficient, and that it will prevent the spreading or tilting of the rail.

It should also be understood that the drawings are merely illustrative and do not pretend to give exact proportions. Furthermore, the said drawings are illustrative of a preferred construction, it being my expectation that various changes and modifications may be made without departing from the spirit and scope of my invention.

What is claimed is:—

1. A rail fastening means including a clamp having the body portion provided with an elongated slot terminating at one end in a lateral notch, means for securing the clamp to a tie passing through said slot, and a second securing means engaging the clamp and tie beyond said slot.

2. A structure of the character set forth, comprising a metallic tie, abutments secured to the tie near the ends thereof, clamps mounted upon the tie between the abutments, each clamp being provided with an opening and with an elongated slot communicating at one end with a lateral notch, a rivet carried by the tie and passing through said slot, and a bolt carried by the tie and passing through said opening.

3. A structure of the character set forth, including a metallic tie provided with a plurality of openings near the ends thereof, hollow abutments having their lower edges resting upon the upper side of the tie and provided at said edges with lugs passing downwardly through the tie and having their lower ends upset to secure the abutments to the tie.

4. A rail fastening means including a clamp having a body portion and a rail web contacting bar secured to one end of said body portion, said bar being provided with bolt receiving openings and said body portion with an elongated slot terminating at one end in a lateral notch, means for securing the clamp to a tie passing through said slot, and a second securing means engaging the clamp and tie beyond said slot.

5. A structure of the character set forth, including a metallic tie provided with a plurality of openings near the ends thereof, hollow abutments having their lower edges 5 resting upon the upper side of the tie and provided at said edges with lugs passing downwardly through the tie and having their lower ends upset to secure the abutments to the tie, and rail web contacting bars

extending laterally from opposite sides of 10 each abutment and provided with bolt receiving openings.

In testimony whereof I affix my signature in presence of two witnesses.

KYLE E. BOYD.
